UNITED STATES PATENT OFFICE

146,361

DESIGN FOR WALLPAPER

Alexander H. Jacobs, New York, and Theresa Anderson, Forest Hills, N. Y., assignors to A. H. Jacobs Company, New York, N. Y., a copartnership

Application May 4, 1946, Serial No. 129,317

Term of patent 7 years

(Cl. D59—10)

To all whom it may concern:

Be it known that we, Alexander H. Jacobs and Theresa Anderson, both citizens of the United States of America and residents of New York, New York, and Forest Hills, Long Island, New York, New York, respectively, have invented a new, original, and ornamental Design for Wallpaper, of which the following is a specification, reference being had to the accompanying drawing, forming a part thereof.

The figure is a plan view of wallpaper showing our new design, the design unit is outlined by the dotted lines, which unit repeats over the wallpaper as indicated by the angles A and A'.

We claim:

The ornamental design for wallpaper, substantially as shown and described.

ALEXANDER H. JACOBS.
THERESA ANDERSON.
